ANCHORAGE MEANS FOR RAILWAY RAILS

Lou Quinn Moore, Pueblo, Colo.

Application August 4, 1944, Serial No. 548,088

2 Claims. (Cl. 238—294)

In an anchorage means for railway rails, it is known to drive, along side the main spike, and at one side of the main spike, in contact therewith, longitudinally considered, an auxiliary spike having a lateral finger overlapping and engaging the head of the main spike. This construction is undesirable, because it enlarges the hole which receives the main spike, and because a hold-down is provided at one side of the main spike only.

In view of the foregoing, one object of the present invention is to provide, in an anchorage means for railway rails, a tie plate having a first opening and provided with second openings disposed on opposite sides of the main opening and spaced therefrom, a spike being extended through the first opening and having a head, recourse being had to a U-shaped staple comprising legs and a bridge connecting the legs, the legs being extended through the second openings, the bridge extending across and engaging the upper surface of the head, and an anchorage hold being provided on both sides of the spike.

Another object of the invention is to supply a device such as is above described, and wherein the axes of the second openings converge upwardly, thereby to spread the legs of the staple as it is driven, and to give the legs of the staple a hold in the tie plate, distinguished from the hold which the legs may have in a tie whereon the plate rests, it being a matter of common knowledge that the tie plate is made of metal, whereas the tie is made of wood or an equivalent substance.

Within the scope of what is claimed, the structure described and shown may be changed, without departing from the spirit of the invention.

In the accompanying drawing:

Figure 1 shows in elevation, a device constructed in accordance with the invention, the tie and the tie plate being shown in section;

Figure 2 is a section at right angles to the cutting plane of Figure 1, a portion of the rail appearing, as a matter of added detail.

In the accompanying drawing, the numeral 1 marks a railroad tie, generally made of wood. A 45 metal tie plate 2 rests on the tie. On the tie plate 2 rests the flange 3 of railroad rail 4.

The tie plate 2 is provided with a first opening

5, and with second openings 6 disposed on opposite sides of the first opening and spaced therefrom.

A metal spike 7 is extended through the first opening 5 and into the tie 1. The spike 7 includes a head 8 overlapping the flange 3 of the railroad rail 4.

A U-shaped, metal staple 9 is provided and comprises legs 10 and a bridge 11 connecting the legs. The legs preferably are parallel before the staple is driven. The legs 10 extend through the second openings 6 and into the tie 1, the bridge 11 extending across and engaging the upper surface of spike head 8. The bridge 11 conforms to the curvature of the upper surface of the spike head 8.

It will be noted that the axes of the second openings 6 converge upwardly, thereby to spread the legs 10 of the staple 9 as it is driven and to give the legs of the staple a hold in the tie plate 2, distinguished from the hold which the legs may have in the tie 1, a secure metal-to-metal grip on the staple 9 being afforded, and the staple constituting an effective means for preventing the spike 7 from working upwardly.

The construction described carries out the objects set forth in the opening portion of this specification.

What is claimed is:

1. In an anchorage means for railway rails, a tie plate having a first opening and provided with second openings disposed on opposite sides of the first opening, and spaced therefrom, a spike extended through the first opening and having a head, and a U-shaped staple comprising legs and a bridge connecting the legs, the legs being extended through the second openings, the bridge extending across and engaging the upper surface of the head.

2. An anchorage means for railway rails, constructed as set forth in claim 1, and wherein the axes of the second openings converge upwardly, thereby to spread the legs of the staple as it is driven, and to give the legs of the staple a hold in the tie plate, distinguished from the hold which the legs may have in a tie whereon the plate rests.

LOU QUINN MOORE.
